UNITED STATES PATENT OFFICE.

CARL SCHMIDT, OF VIENNA, AUSTRIA-HUNGARY.

PURIFYING APPARATUS FOR LIQUIDS.

No. 851,778.

Specification of Letters Patent.

Patented April 30, 1907.

Application filed June 9, 1906. Serial No. 321,074.

To all whom it may concern:

Be it known that I, CARL SCHMIDT, a subject of the Emperor of Austria-Hungary, residing at Vienna, Austria-Hungary, have invented certain new and useful Improvements in Feeders of Precipitants for Water-Purifying Apparatus, of which the following is a clear, full, and exact specification.

This invention relates to a feeder for purifying apparatus for water or other liquids in which a supply of dry powdery precipitating substances is conveyed by means of a worm arranged in the tank containing the precipitating substances, and is then mixed with the water in quantities necessary to dissolve it. In the ordinary water purifying apparatus of this kind, it frequently happens that large particles, more particularly of lime, remain undissolved and are carried away each time that the slime is discharged, so that a considerable portion of the precipitating substance is lost. There is also the drawback that, owing to the increased quantity conveyed by the worm, the precipitating substances are pressed forward toward the end of the tank and packed, so that the worm is stopped by the resistance thus produced. The object of this invention is to do away with the above designated inconveniences.

A construction according to this invention is illustrated, by way of example, in the accompanying drawing, in which:

Figure 1 is a partial longitudinal section. Fig. 2 is a cross-section. Fig. 3 another partial longitudinal section, and Fig. 4 a plan view of an apparatus according to this invention.

The apparatus consists of a tank or vessel *a* for the precipitating chemicals in which is arranged the conveyer worm *b* driven in well known manner, say, by a water pressure motor *c*. Under the tank *a* is arranged a conveyer *d* placed in a casing *e* and also driven by the water motor. This casing is provided, under the outlet opening *f* of the tank *a*, with an enlargement *g* open at the top. A pipe *i*, the cross-section of which is regulated by a cock *h* and which is supplied with water from the water motor casing, opens into the enlargement *g*. In the end wall of the casing *e* there is an opening *k*, the lower edge of which does not quite reach the bottom, and

for this reason large, incompletely dissolved particles of the precipitating agent cannot escape from the tank *e*.

The conveyer worm *b* is provided near the outlet opening *f*, with thread in opposite direction to the thread throughout its length, so that the precipitating substance conveyed forward, cannot be pressed against the end wall, as the reversed front thread will always work back again the precipitating substance toward the outlet opening *f*.

When the apparatus is in operation, the precipitating substance escaping through the opening *f*, together with the water introduced by the pipe *i*, the quantity of which is regulated by the cock *h*, passes into the casing *e*, and is therein dissolved or slaked, and gradually moved backward by the conveyer *d*; all larger particles of the precipitating substance are completely ground and dissolved and in that state mixed with the water to be purified which passes from the water motor through a chute *l*, into a tank below, not shown.

The pipe *i* conveys only the quantity of water required for the complete solution or slaking of the precipitating substance.

Having thus described my invention, what I claim is:

A feeder of chemicals for water purifying apparatus, comprising a compartment *a* for the dry chemicals with a feed worm at the bottom, extending from the outlet opening *f* to the end wall with thread in one direction and from said opening to the opposite end with thread in opposite direction, a compartment *e*, below the compartment *a* with feed opening *g* at one end under the opening *f*; a water supply pipe *i* with cock *h* to admit water for wetting and dissolving a dry chemical, falling down from the compartment *a*, a feed screw *d* in the casing *e* driving the chemicals mixed with the water from the opening *g* at one end toward an opening in the opposite end wall *k*, having its lower edge above the bottom of the casing *a*; and means to impart motion to the feed screws, substantially as described and for the purpose set forth.

In testimony whereof I affix my signature.

CARL SCHMIDT.

In the presence of—
ULYSSES J. BYWATER,
LOUIS F. MUELLER.
